(57) **CLAIM**

The ornamental design for a recording medium, as shown and described.

DESCRIPTION

FIG. 1 is a front, bottom and right side perspective view of a recording medium, showing my new design;

FIG. 2 is an exploded, front, bottom and right side perspective view of FIG. 1 with the cap portion removed;

FIG. 3 is a front elevational view of FIG. 1;

FIG. 4 is a rear elevational view of FIG. 1;

FIG. 5 is a top plan view of FIG. 1;

FIG. 6 is a bottom plan view of FIG. 1;

FIG. 7 is a left side elevational view of FIG. 1;

FIG. 8 is a right side elevational view of FIG. 1;

FIG. 9 is a front elevational view of FIG. 1 with the cap portion removed;

FIG. 10 is a right side elevational view of FIG. 9; and,

FIG. 11 is a bottom plan view of FIG. 9.
